CASE FOR A PHOTOGRAPHIC EXPOSURE METER

Robert John Kingsnorth, Bexley, England, assignor to The General Electric Company Limited, London, England

Application December 2, 1947, Serial No. 142,919
In Great Britain June 6, 1947

Term of patent 14 years

(Cl. D61—1)

To all whom it may concern:

Be it known that I, Robert John Kingsnorth, a citizen of Great Britain, residing at the town of Bexley, in the county of Kent, England, have invented a new, original, and ornamental Design for a Case for a Photographic Exposure Meter, of which the following is a specification, reference being had to the accompanying drawing, forming part thereof.

In the drawing

Fig. 1 is a perspective view of a case for a photographic exposure meter, showing my new design. Fig. 2 is a perspective view of the back of the case from the other side of Fig. 1 and Fig. 3 is a front elevational view of the case showing my new design.

I claim:

The ornamental design for a case for a photographic exposure meter, as shown.

ROBERT JOHN KINGSNORTH.
